UNITED STATES PATENT OFFICE.

CHARLES S. LORD, OF WINOOSKI, VERMONT.

REEL AND SUPPORT.

SPECIFICATION forming part of Letters Patent No. 579,488, dated March 23, 1897.

Application filed April 1, 1896. Serial No. 585,703. (No model.)

To all whom it may concern:

Be it known that I, CHARLES S. LORD, of Winooski, county of Chittenden, State of Vermont, have invented an Improvement in 5 Reels and Their Supports, of which the following description, in connection with the accompanying drawings, is a specification, like letters on the drawings representing like parts.

This invention has for its object the production of a novel reel for holding skeins of 10 yarn in machines for winding the same on spools.

In my invention a series of metallic arms are pivoted on a disk or spider having restrained rotation on a stud, and said arms each have at their inner ends and between their fulcrum and the stud a pin which enters each, a separate spiral slot in a plate which may be rotated more or less on said stud at 15 the side of the said disk or spider, the spiral slots acting on the pins of the arms to simultaneously turn the latter on their fulcrum to enlarge or contract the effective diameter of 20 the reel, and a nut screwed upon the threaded hub of the disk or spider and acting against the slotted plate holding the same in any 25 position in which it may be left.

I have mounted the stud supporting the reel on an arm pivoted on a foot-casting 30 adapted to be secured to a rail of the spooling-machine, the said arm having combined with it means for holding it in proper working position, yet permit it to be thrown or drawn down away from adjacent reels when 35 the yarn of that reel may need attention.

Figure 1, in side elevation, represents a reel embodying my invention mounted on a rail of a spooling-machine; Fig. 2, an enlarged detail showing the slotted plate, disk or spider 40 and parts of the arms pivoted thereon, and the locking-nut; Fig. 3, a section of Fig. 2 on the line $x-x$. Fig. 4 shows one of the reel-arms enlarged; and Fig. 5 is a section in the line $x'-x'$, Fig. 1.

The rail A, commonly extended from one to the other end of a spooling-machine, has attached to it by a suitable bolt a foot-plate B, having a heel B' to fit the back A' of the rail.

The bolt enters a web of the foot-plate and also an ear of a stationary washer a², an up-

right flange of the foot-piece (see Fig. 5) holding a bolt or stud a³, one end of which is passed through the said washer, where it has applied to it a nut a⁴.

55

The bolt is surrounded by a friction device or washer a⁵, and the bolt serves as a fulcrum for the reel-carrying arm b, the setting up of the nut causing the arm to be held with a measured friction, which may be enough to hold the arm in any position in which it may be left, either up or down, as in full or dotted lines, Fig. 1. I also prefer to and have provided the arm b with a pin b', which is adapted to be engaged by a latch b², pivoted at b³ on the washer a².

When the latch engages the pin, as in full lines, Fig. 1, the arm is locked in its elevated position, but when the latch is disengaged from the pin the arm may be turned down more or less to lower the reel mounted on it. The upper end of the arm b has screwed into it the threaded end of a bolt c. The bolt enters the hub of a disk or spider c', and a friction-washer c², and a spiral spring c³, and is screwed into the disk, the threaded end of the bolt receiving a set-nut c⁴ to lock the bolt in place.

The bolt may be screwed into the arm b to compress the spring c³ more or less and cause it to act on the washer to make the latter exert more or less of a restraint on the hub of the disk and restrain it from rotating except after a predetermined amount of strain on the yarn. The spring and washer thus act as a tension device for the reel.

The disk has pivoted upon it at d a series of arms d', having at their inner ends each a like pin d', which enters one of a series of spiral slots d² in a plate d⁴, mounted on the extended hub of the disk c', the said hub being threaded and receiving a locking-nut d⁵, which may be made to lock or unlock the plate, the latter when unlocked being free to be moved on the hub in one or the other direction to cause the arm to assume a more or less radial position with relation to the disk which constitutes the hub of the reel, such movement of the plate expanding or contracting the reel. The reel-arms d' have combined with them extension-arms e', suitably connected thereto and provided at their outer ends with skein-

holders e^2 . A series of these arms d' e' and skein-holders e^3 make up the reel.

I have shown the rear ends of the arms e' as provided with a T-piece e^4 and so bent as 5 to enter the slots e in the arms d' , and the arms e' are shown as slotted at e^4 to receive a screw e^5 , inserted in the arms d' .

The arms may be lengthened and shortened at will by loosening the screws e^5 , and all of 10 them may be simultaneously inclined more or less quickly to take off a skein or to adapt the arms to the size of the skein being applied. The arms e' , near their outer ends, have given 15 to them a quarter-twist, as at f , so as to turn to the proper angle the skein-holders.

The disk d^4 has ears or thumb-pieces 10, which may be engaged easily when the disk is to be turned to enlarge or contract the skein-holding arms.

20 Having described my invention, what I claim as new, and desire to secure by Letters Patent, is—

1. A series of arms having at one end skein-holders e^2 , and at their other ends pins d^2 , the 25 disk or spider having an elongated hub on which said arms are pivoted at d between their ends, and the plate having a series of spiral slots to receive said end pins d^2 , said plate being mounted on the hub of said disk or spider, 30 combined with a locking device on said hub to coöperate with said plate, the partial rotation of the plate when unlocked enabling all the arms to be adjusted simultaneously, the locking of the plate locking all the arms in 35 position; a stud on which said disk is mounted, and an adjustable restraining device coöper-

ating with said disk to restrain its rotation more or less as required, substantially as described.

2. The series of longitudinally-adjustable 40 arms having at one end skein-holders e^2 , and at their other ends pins d^2 , the disk or spider having an elongated hub on which said arms are pivoted at d between their ends, and the plate having a series of spiral slots to receive 45 said end pins d^2 , said plate being mounted on the hub of said disk or spider, combined with a locking device on said hub to coöperate with said plate, the partial rotation of the plate when unlocked enabling all the arms to be adjusted simultaneously, the locking of the plate locking all the arms in position; a stud on which said disk is mounted, and an adjustable restraining device coöperating with 50 said disk to restrain its rotation more or less 55 as required, substantially as described.

3. The foot B , having an upright provided with a bolt, and a reel-carrying arm mounted on said bolt, a friction-washer arranged at one side of said arm, and an adjustable washer 60 arranged at its other side to act as a clamp, combined with means to restrain the rotation of the said adjustable washer whereby said arm may be held in any position in which it may be left, substantially as described. 65

In testimony whereof I have signed my name to this specification in the presence of two subscribing witnesses.

CHARLES S. LORD.
